UNITED STATES PATENT OFFICE.

ARTHUR WILLIAM WHISTLECROFT, OF LONDON, AND HAROLD ROBERT CORBY VAN DE VELDE, OF BROMLEY, ENGLAND, ASSIGNEES TO RADIO CORPORATION OF AMERICA, OF NEW YORK, N. Y., A CORPORATION OF DELAWARE.

WINCH.

Application filed October 25, 1920. Serial No. 419,202.

To all whom it may concern:

Be it known that we, ARTHUR WILLIAM WHISTLECROFT and HAROLD ROBERT CORBY VAN DE VELDE, subjects of Great Britain, residing at 81 Baker Street, London, W. 1, and 57 Ravensbourne Road, Bromley, in the county of Kent, England, respectively, have invented certain new and useful Improvements in Winches, of which the following is a specification accompanied by drawings.

This invention relates to winches, and its object is to provide an improved winch which can be turned to wind in by means of a handle, is normally braked when the handle is released and can by the movement of the handle through a small angle be freed to let the load run out.

According to our invention we provide a winch barrel with a friction brake which normally holds the barrel from rotating, through which the barrel can be rotated in one direction to wind in and which can be withdrawn from engagement with the barrel so that the latter is free to turn in the opposite direction under the pull of the load whilst the handle is stationary.

Our invention is illustrated by the accompanying drawings, Figure 1 of which is a vertical section through a winch suitable for controlling a trailing aerial on an aeroplane, while Figure 2 is an elevation.

a is a winch barrel which has formed in one with it a brake drum *b* engaged by a brake band *c*; the barrel is loosely mounted upon a sleeve *d* provided with a handle *e* by means of which it can be turned on a stud *f* projecting out from a fixed plate *g*. One end of the band *c* is fastened to a pin *h* carried by an arm *i* on the sleeve *d* while the other end is fastened to a pin *j* carried by a ratchet wheel *k* with which meshes a detent *l* pivoted to the plate *g*. The natural spring of the band *c* keeps it pressed hard against the drum *b*. Normally the barrel is held stationary by the pressure of the band *c* which is itself held stationary by the engagement of the detent *l* with the ratchet wheel *k*. When it is desired to wind in the handle *e* is rotated clockwise as seen in Figure 2, the band *c* being thereby pressed harder against the drum *b* and rotating the barrel, the wheel *k* running past the detent *l*. When it is desired to let the aerial run out the handle is turned slightly anti-

clockwise, thus bringing the pin *h* nearer to the pin *j* thereby contracting the band *c* and leaving the barrel *a* free to rotate on the sleeve *d* under the pull of the aerial, whilst the handle remains stationary.

Having now particularly described and ascertained the nature of our said invention and in what manner the same is to be performed, we declare that what we claim is:

1. In a winch, the combination of a winding drum, a friction brake located within said drum and adapted normally to engage the inner surface of said drum to hold the same stationary and means for driving said drum through said brake and for releasing said drum from said brake. 70

2. In a winch, the combination of a winding drum, a friction brake located within said drum and adapted to engage the inner surface thereof, a winding handle for driving said drum through said brake and means operated by back pressure on said handle for releasing said brake whereby the handle is stationary when the drum is revolving to run out the load. 75

3. In a winch, the combination of a winding drum, a friction brake located within said drum and adapted to engage the inner surface thereof, a winding handle for driving said drum through said brake and means operated by back pressure on said handle for controlling the friction of the brake whereby the handle is stationary when the drum is revolving to run out the load and the speed of the drum is governed. 85

4. In a winch, the combination of a winding drum, a friction brake located within said drum and adapted normally to engage the inner surface thereof to hold the drum stationary, a handle for driving said drum through said brake by rotation in one direction and for controlling the friction of the brake by back pressure on said handle when said drum is rotated by running out the load. 95

5. In a winch, the combination of a winding drum, a friction brake located within said drum and adapted normally to engage the inner surface thereof, a stationary support, means comprising a spring for pressing said brake against said drum normally to hold the barrel stationary, a winding handle connected to said spring for driving the drum through the brake and means 105

- 2
- comprising a pawl and ratchet cooperating with said handle when back pressure is applied thereto for controlling the friction of the brake to permit the load to run out.
- 5 6. In a winch, the combination of a winding drum, a friction brake located within said drum and normally maintained in engagement with the inner surface thereof, a stationary support, means cooperating with
- 10 said support and with said brake to permit rotation in one direction only of said brake, a winding handle, said handle being connected to said brake for driving the drum through the brake by rotation thereof,
- whereby when back pressure is applied to 15 said handle said brake is released.
7. In a winch, the combination of a winding drum, a friction brake located within said drum and adapted to engage the inner surface thereof, a ratchet wheel connected to one end of said brake, a support having a winding handle and a connection between said winding handle and the other end of said brake for driving said drum through said brake.
